ORNAMENTATION

Alfred F. Reilly, North Attleboro, Mass., assignor
to Evans Case Company, North Attleboro,
Mass., a corporation of Massachusetts

Application September 9, 1937, Serial No. 163,120

12 Claims. (Cl. 41—35)

The invention relates generally to the production of an ornamental sheet or plate composed preferably of some such material as celluloid or like plastic and some such material as metal or like rigid material. The metal preferably is formed into an ornamental sheet which may be very thin and may be perforated with such holes as may be necessary to form the desired ornamental appearance. Such a metal sheet will 5 preferably be very thin and may be formed by any suitable process such as etching, electro-plating, stamping, or other process of the sort.

Such a metal sheet may be applied to the surface of a sheet of celluloid. If desired adhesive 15 may be applied to the metal sheet by spraying or otherwise and before it is placed on the celluloid sheet. This may aid in holding it in place during manipulation. The celluloid sheet preferably is transparent and it may be colored wholly or partially and the color may be distributed in any 20 suitable manner. A plurality of colors may be employed, the color being applied either to the surface of the celluloid or worked into the celluloid.

The size and shape of the celluloid is immaterial in some aspects of the invention. It may be the same size as the metal sheet or as the desired final product, or it may be of a larger size and subsequently cut to the desired final size. 25 A second sheet of metal similar to the first sheet may be provided in any suitable way. The second sheet will be placed on the side of the celluloid opposite the first sheet and to fix it may if desired have applied to it adhesive in a similar manner. The sheets preferably will have corresponding perforations identical in size and shape and arranged opposite each other on the opposite sides of the celluloid sheet. Preferably the celluloid sheet will be somewhat thicker than the 30 combined thicknesses of the two metal sheets. 40 The two metal sheets having been put in position on the celluloid sheet the entire mass may be placed between heated polished dies which may cause the celluloid to become plastic and may force the ornamental metal sheets into both surfaces of the celluloid sheet until the metal sheets become substantially level with the respective surfaces of the celluloid sheet. In this arrangement there will preferably be left an undisturbed portion of the celluloid sheet between the metal sheets although this may not be essential. The metal sheets may be brought into substantial contact with each other. During the pressing operation the metal sheets sink into the surfaces 50 of the celluloid and the celluloid rises in all of the

perforations or apertures of the metal sheets, thus forming a smooth, polished surface on each side of the celluloid giving the appearance of a single metal sheet with perforations filled with celluloid.

The finished ornamented sheet may be made from metal sheets which have continuous metallic edges although this is not essential. Such an arrangement is particularly convenient when the finished sheet is to be placed into a frame or 10 casing or cover of metal since the metallic apertures may be readily attached to the metal frame into which the finished sheet is to go.

The invention may be carried out practically in the manner indicated in the accompanying drawing in which Figure 1 is a plan view of a finished ornamental sheet mounted in a metallic frame, a portion of the design being indicated diagrammatically. Fig. 2 is a fragmentary transverse vertical section on the line 2—2 of Fig. 1. Fig. 3 is a fragmentary vertical section diagrammatically illustrating the formation of the sheet in heated dies, the dies being open. Fig. 4 is a view similar to Fig. 3 the dies being closed. Fig. 5 is a fragmentary view similar to Fig. 3 showing 25 a special type of die.

The ornamental metal sheets 10 having been formed in any suitable manner may have adhesive 11 applied to them and by means of the adhesive they may be positioned on opposite sides 30 of the celluloid sheet 12 in such manner that the corresponding perforations such as 13 in the two sheets are directly opposite each other. For illustrative purposes the adhesive is shown as much thicker than needed or used. In this condition and preferably after the adhesive has been dried the assembled sheets may be placed between the smooth, polished, heated dies 14 and the dies may be brought together as indicated in Fig. 4. The metal sheets may be properly adjusted in 35 registry on the opposite sides of the celluloid and so held in any suitable way and without the use of adhesive. Preferably the dies will be so adjusted and controlled that when they are closed together they leave between them an aperture 40 substantially the width of the original celluloid sheet 12. The combination of the heat and pressure causes the upper and lower metal sheets 10 to enter the celluloid sheet 12 portions of which 45 exude into the apertures 13 filling them and forming a smooth, polished surface on both sides of the finished ornamented sheet. As illustrated in Figs. 3 and 4 the original celluloid sheet may 50 extend beyond the edges of the metal sheets and if desired the finished sheet may be cut into suit- 55

able form the extra edges of the celluloid being discarded. In Fig. 5, however, is indicated another scheme in which one of the dies 15 has a projecting edge 16 which may outline the size 5 of the final sheet desired. Thus there may be placed into the die 15 a pre-formed ornamental metal sheet 10 the exact size of the die and the exact size desired for the finished product. On this may be placed a sheet of celluloid of the exact 10 size desired of the finished product and on this may be placed a second ornamental metallic sheet 10 of the same size. Thus the desired registry of the apertures in the metal sheets may be insured without manipulation or the use of adhesive. A suitable form or plunger die 17 of the 15 same size may enter the aperture 16 and by heat and pressure cause the ornamental metal sheets 10 to assume positions within and at the surface of the celluloid sheet. In this operation a finished sheet of desired size may be provided which has no flash of celluloid and which needs no trimming before use.

The celluloid sheet 12 may be provided with color in any suitable way. This color persists 25 throughout the operation and the final product is a sheet ornamented by the metal plates 10 and further ornamented by the color effect of the celluloid. The color effect may be produced by printing or otherwise applying the color to the 30 celluloid in such a manner that the voids in the metallic pieces will be filled with various colors to produce various color designs. There may thus be produced plates, plaques, pictures, windows and the like. By this operation it may be 35 possible to produce imitations of leaded glass windows such as are ordinarily used in churches, auditoriums and the like. Further use for the invention is in the manufacture of such devices as compacts, vanity cases, cigarette cases, cigarette 40 holders, mirrors, brushes and the like.

The ornamental sheet may be mounted in any suitable manner. In Fig. 1, for instance, is illustrated a metallic frame which may form the cover for a box or compact or the like. This 45 metallic cover may comprise an outer frame 20 provided with an inner ledge 21 on which the ornamental sheet 10, 12 may rest. In the drawing a sheet is illustrated in which the metallic sheets 10 are integral throughout their margins 50 and these metallic margins may be attached in any suitable manner to the lip 21 of the frame member 20, it being particularly convenient to attach metal to metal.

The metallic sheets 10 may be made of very 55 thin metal so that they may be flexible and easily handled. They are not, however, deformed during manipulation but retain their size and ornamental shape. To this extent therefore, they are rigid and the term rigid has been employed in 60 the accompanying claims to refer to this characteristic in contradistinction to the characteristic of the celluloid sheet which does deform under manipulation. The celluloid sheet itself is flexible and it may be desirable to employ two 65 metal sheets of such thinness that the finished sheet consisting of the celluloid sheet and the two metal sheets, one in each surface, is flexible to some extent as a whole although when the metallic sheets have been fixed into the celluloid 70 sheet the entire sheet becomes rigid in the sense that it does not deform and lose its ornamental appearance. While this flexibility is not an essential element of the present invention it may be an important element in the usefulness of the 75 invention when applied to articles of personal

use such as compacts and like devices carried on the person since it is possible for them to bend without breaking or marring.

The invention has been described as relating to metal sheets and celluloid sheets although it is obvious that sheets of other rigid material may be similarly associated with sheets of other plastic material, and the terms metal and celluloid are here employed as relating respectively to rigid and plastic materials generally.

The relative size, form and proportions of the various elements have been shown to make the invention clear but with no intention of so limiting the invention. The invention may be capable of embodiments other than those here described.

I claim as my invention:

1. The method of ornamenting comprising placing a thin sheet of perforated ornamental metal on one side of a smooth sheet of transparent celluloid, placing a similar thin sheet of perforated metal on the surface of the other side of the celluloid with the perforations of the metal sheets in register, and pressing the assembly between heated polished smooth dies till the metal sheets enter the celluloid and become level with its surfaces respectively.

2. The method of ornamenting comprising placing a thin sheet of perforated ornamental metal in a heated smooth polished die of the same size as the metal, placing on the metal in the die a sheet of celluloid of the same size but more than twice the thickness of the metal, placing on the celluloid in the die a similar sheet of perforated ornamental metal, and pressing with a heated polished smooth die till the metal sheets enter the celluloid and become level with its surfaces respectively.

3. The method of ornamenting comprising applying an adhesive on one side of each of two similar thin sheets of perforated metal, placing the metal sheets on the opposite surfaces of a sheet of celluloid with the adhesive toward the celluloid, and with the perforations opposite each other, and pressing the assembly between heated polished smooth dies till the metal sheets enter the celluloid and become level with its surfaces respectively.

4. A sheet of celluloid having sunken into each side to the surface a thin perforated metal sheet the perforations of the sheets being in register.

5. The method of ornamenting celluloid comprising sinking into the celluloid on each side of the surface a thin perforated metal sheet, and keeping the perforations of the sheet in register.

6. A sheet of celluloid having sunken into each side of the surface a thin perforated metal sheet extending to the edges of the celluloid and the perforations of the sheets being in register.

7. The method of ornamenting celluloid comprising sinking into the celluloid on each side to the surface a thin perforated metal sheet extending to the edges of the celluloid and keeping the perforations of the sheets in register.

8. The method of ornamenting comprising placing a thin sheet of perforated metal in a heated smooth polished die the same size as the metal, placing on the metal in the die a sheet of celluloid of the same size, placing on the celluloid a similar sheet of perforated metal, and pressing with a heated polished smooth die till the metal sheets enter the celluloid and become level with its surfaces respectively.

9. A sheet of transparent plastic having sunken into each side to the surface a thin per-

forated rigid sheet the perforations of the sheets being in register.

10. The method of ornamenting comprising sinking into a sheet of transparent plastic on each side to the surface a thin perforated rigid sheet, and keeping the perforations of the sheets in register.

11. A sheet of celluloid having sunken into each side to the surface a thin perforated metal sheet extending to the edges of the celluloid and

the perforations of the sheets being in register, and a frame to which it is attached by the metal edges.

12. The method of ornamenting comprising sinking into a sheet of celluloid on each side to the surface a thin perforated metal sheet extending to the edges of the celluloid, and keeping the perforations in register, and fastening the sheet into a frame by its metal edges.

ALFRED F. REILLY. 10
